CONTAINER FOR AN ELECTRIC LAMP

Milton Liberman, 65 Sewane Road, East Rockaway, N.Y.

Filed Dec. 22, 1964, Ser. No. 83,120

Term of patent 14 years

(Cl. D58—11)

Fig. 1.

Fig. 2.

Fig. 3.

T 19-4-

The broken line showing of a part of an electric lamp in FIGURE 1 is for illustrative purpose only.

I claim:

The ornamental design for a container for an electric lamp, as shown and described.
